UNITED STATES PATENT OFFICE.

WILLIAM A. GIBSON, OF MUSCATINE, IOWA, ASSIGNOR OF ONE-HALF TO
JAMES W. DE FOREST, OF SAME PLACE.

FEED-WATER HEATER.

SPECIFICATION forming part of Letters Patent No. 669,921, dated March 12, 1901.

Application filed June 16, 1900. Serial No. 20,605. (No model.)

To all whom it may concern:

Be it known that I, WILLIAM A. GIBSON, of Muscatine, in the county of Muscatine and State of Iowa, have invented certain new and useful Improvements in Feed-Water Heaters; and I hereby declare that the following is a full, clear, and exact description thereof, reference being had to the accompanying drawings, which form part of this specification.

10 This invention is an improved feed-water heater for steam-boilers and is adapted for use in connection with all cylinder-boilers, especially locomotive and fire-tube boilers, and is also useful in connection with hot-water heating apparatus.

15 The invention consists of a simple and novel device by which the water as it is fed to the boiler is raised to a high temperature before being admitted into the water-space of the 20 boiler, and the accompanying drawings illustrate the device as applied to a fire-tube or locomotive boiler.

25 Referring to said drawings, Figure 1 is a sectional elevation of part of a boiler with my improved feed-water heating device applied thereto and indicating, conventionally, a feed-water injector and water-supply tank. Fig. 2 is an enlarged sectional view through the heating device detached.

30 A designates a boiler of any ordinary construction, that shown being of the fire-tube locomotive type, having a water-space B surrounding the tubes, above which is the steam-space C, and at the end of the boiler is a 35 smoke-box D. Projecting into the steam-space B through the boiler-head is a horizontally-arranged tube E, which is closed at its inner end by an enlarged cap F, which has a central inwardly-projecting conical baffle- 40 plate f. The outer end of tube E within the smoke-box D is closed by a hollow head G, which is connected by a pipe H within the

45 smoke-box with the water-space B near the bottom thereof, a stop-cock h being placed in this pipe H for the purpose hereinafter explained. Extending through the head G and into the tube E is a pipe I of smaller diameter than the tube E. The inner end of pipe I lies close to the conical baffle-plate f and directly 50 opposite the latter, and the pipe I extends through the head G and through the smoke-

box D to the exterior of the boiler, where it is connected by a pipe J with an injector K or any suitable feed-water-forcing device, the water being supplied to the injector from the 55 tank W. Pipe I is provided at a suitable point, preferably exterior to the smoke-box, with a check-valve j to prevent back pressure from the boiler. Preferably all the pipes within the boiler, and especially the parts 60 within the steam-space, are lined or coated with zinc to prevent corrosion.

The operation of the apparatus is as follows: The feed-water is propelled through the pipes I and J into the tube E and discharged 65 against the baffle-plate f, the conical surface of which causes a spraying and dissemination of the water in head F, and this spray rebounds back into the tube E, and as both the baffle-plate and the tube E are subjected 70 to the intense heat of the superheated steam in the space C the dispersed water flowing through the tube E is immediately raised to a high temperature, which is maintained or augmented by its passing through the head G 75 and pipe H to the boiler, since head G and pipe H are located in the smoke-box directly opposite the outlets of the fire-tubes and subjected to the intense heat of the products of combustion escaping into the smoke-box. The 80 spraying of water caused by the baffle-plate f and the sudden rise of the temperature of the water in the tube E create a partial vacuum within the tube E, which largely relieves the check-valve j of back pressure. 85

The stop-cock h is preferably located within the smoke-box, and when this stop-cock is closed the heater will be out of action, and, if desired, the check-valve j can be inspected without danger and the pipes I and J can 90 be removed without arresting or in any way interfering with the ordinary action of the boiler.

As the water is discharged into the lower part of the boiler at a high temperature, there 95 is no danger of foaming, and the sediment and refuse will be forced to the forward part of the boiler, where they can be more easily removed.

Where upright boilers are used, the pipe 100 H may be extended through the steam-space to the point below the water-line. Where

two injectors are used, both of them may be connected directly to the pipe I, so that they can work independently of each other or both together without interfering with the 5 operation of the heater.

By this apparatus a continuous uninterrupted supply of hot water may be maintained to the boiler and the water be raised to a high temperature before it enters into 10 the water-space of the boiler.

Having thus described my invention, what I therefore claim as new, and desire to secure by Letters Patent, is—

1. In a feed-water heater for boilers, the 15 combination of the boiler, a tube arranged in the steam-space thereof and projecting through the walls of the boiler, a baffle-plate closing the inner end of the tube and a head on the exterior end of the tube; with a pipe 20 connecting the outer end of said tube with the water-space of the boiler; a water-supply pipe extending through the head into said tube and to a point directly opposite and adjoining the baffle-plate, and means for forcing 25 water through said pipe into said tube, substantially as and for the purpose described.

2. The combination with a boiler, of the tube arranged in the steam-space thereof and projecting through the walls of the boiler, 30 the head on the inner end of said tube provided with a conical baffle-plate, and a head on the outer end of said tube, a pipe connecting said outer head with the boiler and the pipe extending through the outer head 35 into the tube to a point directly opposite the baffle-plate, for the purpose and substantially as described.

3. In a feed-water heater for steam-boilers, the combination with a boiler, of a tube arranged in the steam-space thereof and projecting through the walls of the boiler, the head on the inner end of said tube provided 40 with an internal conical baffle-plate, a hollow head on the outer end of said tube, a pipe 45 connecting said outer head with the boiler below the water-level and the pipe extend-

ing through the outer head into said tube to a point directly opposite the baffle-plate, a check-valve in said pipe and means for forcing water through said pipe into the tube, for 50 the purpose and substantially as described.

4. The combination of a boiler, the tube extending into the steam-space of the boiler having a head on its inner end within the steam-space provided with a baffle-plate, and 55 a head on its outer end, a pipe connecting the outer head with the water-space of the boiler near the bottom thereof, and a stop-cock in said pipe; with a pipe extending through said outer head into said tube to a 60 point directly opposite the baffle-plate on the inner head, said pipe also extending through the smoke-box to the exterior thereof and connecting with a water-supply pipe, and a check-valve in the water-supply pipe, all substantially as and for the purpose described.

5. The combination of the boiler having a smoke-box, the tube extending from the smoke-box into the steam-space of the boiler having a head on its inner end within the 70 steam-space provided with a baffle-plate, and an enlarged head on its outer end within the smoke-box, a pipe connecting the outer head with the water-space of the boiler near the bottom thereof, and a stop-cock in said pipe; 75 with a pipe extending through said outer head centrally of said tube and to a point directly opposite the baffle-plate on the inner head, said pipe also extending through the smoke-box to the exterior thereof and connecting with a water-supply pipe, a check-valve in the water-supply pipe, and an injector for forcing water through said pipe, 80 all substantially as and for the purpose described.

In testimony that I claim the foregoing as my own I affix my signature in presence of two witnesses.

WILLIAM A. GIBSON.
